[57] CLAIM

The ornamental design for a door edge draft shield,
substantially as shown.

DESCRIPTION

FIG. 1 is a perspective view of the present design,
showing a break in the center portion to denote indefinite
length;

FIG. 2 is an end view thereof;

FIG. 3 is a front elevational view thereof, showing a
break in the center portion to denote indefinite length;
FIG. 4 is a top view thereof, showing a break in the
center portion to denote indefinite length;

FIG. 5 is a rear elevational view thereof, showing a
break in the center portion to denote indefinite length;
and

FIG. 6 is a bottom view thereof, showing a break in the
center portion to denote indefinite length.
